G. M. BROWNING

PHONOGRAPH RECORD

Filed Dec. 27, 1922

FIG. 1

FIG. 2

FIG. 3

FIG. 4

INVENTOR

George M. Browning

BY Parker W. Page

his ATTORNEY

UNITED STATES PATENT OFFICE.

GEORGE M. BROWNING, OF RUTHERFORD, NEW JERSEY.

PHONOGRAPH RECORD.

Application filed December 27, 1922. Serial No. 809,211.

To all whom it may concern:

Be it known that I, GEORGE M. BROWNING, a citizen of the United States of America, residing at Rutherford, in the county of Bergen and State of New Jersey, have invented certain new and useful Improvements in Phonograph Records, of which the following is a full, clear, and exact description.

10 It is not unusual at the present time to make phonograph records of celluloid or similar pyroxyline compounds, and for certain purposes it is desirable that they be quite thin; so thin, in fact, that it is difficult to keep them flat, or prevent them warping or bulging, especially where the central hole is of such dimensions or character that the material of the disk is gripped by the central pin of the phonograph turn-table when the record is in place, and thereby forced up in a cone, or the record otherwise distorted. It will be understood that unless the record, while being played, is perfectly flat, it does not function properly.

15 Another objection to such light and thin records is their tendency to slip over the surface of the turn-table and thus remain stationary thereon under the contact pressure of the reproducing needle, and this objection becomes the more serious as the diameter of the record disk is reduced.

To improve records of this character so as to prevent them bulging, wrinkling or becoming distorted when in use, and to prevent their slipping over the turn-table and remaining stationary when not secured to the central pin, is the object of my present invention, and the subject of this application for patent.

20 In carrying out this invention I provide for a thin celluloid or equivalent record a strengthening or reinforcing means. If the record be of any considerable diameter, say, seven to ten inches, it is preferable to use 25 for such reinforcement a metallic strip which is bent over the outside edge of the disk and secured thereto by pressure. If the record be smaller than this, the reinforcement may be secured by impressing in 30 the material of the record one or more annular corrugations or ridges at points where there are no record grooves. In either case, this reinforcing keeps the disk flat and free from distortion.

35 In order to increase the gripping power of the disk, and not to rely on friction with

the turn-table alone, I form in the metal band or in corrugations teeth, which enter the soft felt or material covering the turn-table and resist slipping of the disk thereon. Such teeth may be most readily and conveniently formed by pressing out the material and should be in the general nature of saw-teeth, turned in a direction to more fully resist relative movement of the disk 65 and the turn-table.

In more detail the improvements are illustrated in the accompanying drawing and referred to in the description of the same which follows:

70 Fig. 1 is a plan view of a disk embodying my invention.

Fig. 2 is a cross-sectional view of a large disk with an applied metal reinforcement.

Fig. 3 is a vertical view of a small record 75 with the reinforcements impressed therein; and,

Fig. 4 is an enlarged view of the saw-teeth, in this case formed by the displacement of the record material in the corruga- 80 tions forming the reinforcement.

Referring to Fig. 1, the numeral 1 designates a phonograph record composed of a thin sheet of celluloid in which by the usual and well known process a record 85 groove has been pressed. This disk record has a central hole 2 through which the spindle of the phonograph will pass when the disk is put on the instrument for playing. Around the edge of the disk is a metal band 90 3. This may be of tin or other metal and is doubled over the edge and pressed into close union with the disk. This band should possess sufficient rigidity to prevent the disk from warping, bulging or becoming 95 distorted when in use.

In Fig. 3 a smaller disk of the same material is shown. Such a disk does not require an applied reinforcement, as it may be given sufficient rigidity or resistance 100 to distortion by forcing the material to form corrugations or ribs 4, near its outer edge, or both outer sides 4, and another rib or corrugation 5 near its center at a point where there are no record grooves.

If the disk has a record on both sides, the corrugations, instead of being of substantially a U-shape, may be double or more nearly like the letter S in conformation.

105 In the case of either of the disks above described, the tendency of the same to slip over the surface of the turn-table may be

counteracted by forming saw-teeth 6 in the reinforcement. These teeth may be pressed or punched out of the metal reinforcement 2, as shown at 7 in Figs. 1 and 2, or pressed 5 or punched from the material of the disk itself, and in this case they will project from the high points of the corrugations or ribs, which, serve as the reinforcements.

The teeth are formed approximately as 10 shown in Fig. 4, so as to engage the woolly surface of the turn-table which normally moves in the direction of the arrow.

The invention is not limited to the specific 15 form or character of the reinforcement herein shown and described, nor to the particular method of making or applying the saw-teeth above set forth, but what I claim as my invention is:

1. A phonograph record disk of thin 20 flexible material such as celluloid having impressed therein annular corrugations in a part of the disk where there is no record groove, said corrugations projecting from both sides of the disk and designed and 25 adapted to maintain the same in a flat condition when in use.

2. A phonograph record disk of thin flexible material such as celluloid having punched from a part where there is no record groove pointed portions in the nature 30 of saw teeth designed and adapted to engage the surface of the record support to resist slipping thereon.

3. A phonograph record disk of thin flexible material such as celluloid having an- 35 nular corrugations impressed in parts of the disk where there is no record groove and pointed portions punched from the high points of such corrugations in the nature of saw teeth designed and adapted to engage 40 the surface of the record support to resist slipping thereon.

4. A phonograph record of thin flexible material such as celluloid having impressed therein around its outer edge and near its 45 center where there is no record groove, annular reinforcing corrugations or ribs designed and adapted to maintain the same in a flat condition when in use.

In testimony whereof I hereto affix my 50 signature.

GEORGE M. BROWNING.
